ARTHUR JAMES POSTANS, OF LONDON, ENGLAND, ASSIGNOR TO THE ADDER CASH REGISTER SYNDICATE, LIMITED, OF LONDON, ENGLAND.

PRINTING MECHANISM FOR CASH-REGISTERS OR LIKE MACHINES.

1,033,928.

Specification of Letters Patent. Patented July 30, 1912.

Application filed March 6, 1909. Serial No. 481,630.

To all whom it may concern:

Be it known that I, ARTHUR JAMES POSTANS, a subject of the King of England, residing at London, England, have invented 5 certain new and useful Improvements in Printing Mechanism for Cash-Registers or Like Machines, of which the following is a specification.

This invention is for improvements in or 10 relating to printing mechanism for cash registers or like machines, of the type wherein the item recording mechanisms when zeroized advance the total recording mechanisms by such zeroizing movement, 15 and relates particularly to mechanism for printing or recording totals.

In cash registers and like machines where provision is made for printing or recording both the items and totals, the item mechanism or recorder being zeroized after each 20 operation, such zeroizing movement has, as is well known, been employed to advance the total mechanism or recorder so that as each item is zeroized it is added to the total.

25 The present invention relates to a machine of this class wherein the item mechanisms and total mechanisms coöperate in the manner stated, but such coöperation forms no part of the present invention. 30 The machine comprises a plurality of item mechanisms, one mechanism or set of members being allotted to each order of value to be recorded as items, such for example as shillings and pence, and a plurality of total recording mechanisms also allotted one to 35 each order of value to be recorded as totals and that receive their motion from the zeroizing of the item mechanisms as described.

It will be understood that as usual some 40 "carrying-on" device must be employed between the mechanisms for the different orders of value in the total-recording apparatus and if "carrying-on" takes place at the moment when the mechanism, to which 45 transference is taking place, is being operated direct from its own set of item mechanism, the amount to be "carried-on" is liable to be lost.

The object of the present invention is to 50 insure that "carrying on" and adding direct from the item mechanism should not take place simultaneously on the same set of total-recording mechanism.

According to this invention the total re- 55 corder is directly operated by the item re-

corder as this is zeroized, but a device is provided that prevents "carrying-on" in the total recorder to any higher order that is to be itself directly operated from the item recorder until such direct operation has 60 been effected. It is obvious that the total may be recorded by drums carrying numerals that are presented opposite a reading slot, or the drums may be made in the form of printing drums and the total printed 65 when desired, and for the purpose of this invention the machine will be described as arranged to print the total.

For the present invention a series of item printing drums are employed, the various 70 drums representing different orders of value; these drums with their operating mechanism may be termed the item recorder. The drums are displaced by the operation of the keys against a yielding control and mechanism is provided whereby 75 those of the drums operated, representing the highest order of value, prevent the drums of those representing the next lower order of value from operating until they 80 have themselves returned to zero. The object of this arrangement is to enable a second series of printing drums (which with their operating mechanism may be termed the total recorder) to be operated by the return 85 movement of the first series whereby the items printed by the first series are totaled on the second series, and unless the item drums were returned according to their successive orders of value, proper "carrying-on" 90 by the total drums would not be effected.

In addition to the means for checking the order of return of the item drums, or other item mechanism, the mechanism for each 95 drum is controlled by a returning pawl that normally is in operative position. These pawls are arranged to be displaced by the printing key for the purpose of permitting the return of the item mechanism, under the 100 action of its yielding control, and for effecting the operation of the total mechanism. Preferably the device for releasing the pawls is arranged to operate them in succession, for instance, that holding the drum 105 of highest order may be first freed and then that holding the drum of the next lower order, and so on.

In the accompanying drawings, which 110 illustrate one method of carrying out this

invention:—Figure 1 is a perspective view of the item and total-recording mechanisms, and Fig. 2 is a side elevation of that part of the machine which relates to the printing, 5 and Fig. 3 is an end elevation of the mechanism illustrated in Fig. 1.

Like letters indicate like parts throughout the drawings.

The keys (not shown) operate two quadrants A, A¹ which are yieldingly controlled 10 as by springs a. The quadrant A gears with the wheel B that is carried fast on a shaft C and the quadrant A¹ gears with a wheel B¹ that is fast on a hollow shaft C¹. The shafts 15 C, F C¹ F¹ carry on their ends printing drums N, N¹, N², N³ which form no part of the present invention, but it will be seen that any number of shafts with their printing drums and operating quadrants may 20 thus be arranged, the shafts being nested one in the other and the drums being arranged side by side on any suitable part of the machine. Each quadrant with its operating mechanism is allotted to a particular 25 order of value, for instance the quadrant A with its mechanism may be operated by keys representing pounds, while the quadrant A¹ may be operated by the keys representing shillings, and another quadrant with its 30 operating mechanism may represent pence, and so on.

The wheel B meshes with a wheel D, that is free on a shaft E, and this wheel with the other parts that are operated thereby, constitute 35 that portion of the total recorder mechanism that is allotted to the order of value represented by the keys that control the quadrant A. The wheel B¹ also meshes with a wheel D¹ free on the shaft E, and each wheel 40 D, D¹ carries a pawl arm and pawl mechanism that coöperates with pin wheels D², also free on the shaft E. Only one pin wheel is shown in the drawing, and as the pawl mechanism is the same as that shown in Fig. 45 3 of the earlier specification No. 851433 dated 23rd April 1907 and forms no part of the present invention, there is no necessity to illustrate and describe these parts in the present specification. Each pin wheel carries 50 a toothed wheel D³ (one only being shown) and the wheels D³ engage toothed wheels D⁴ and D^{4*} on a counter shaft. In Fig. 1 the wheel D^{4*} which would engage 55 with the wheel D³ on the right is removed to show the wheel D³ but on the left of the drawing the wheel D⁴ is shown and behind it and hidden by the counter-shaft and wheel is a wheel D⁵ corresponding to that shown on the right. But in Fig. 3 the wheel 60 D^{4*} is shown engaging one of the wheels D³. The wheel D⁴ on the left of Fig. 1 is fast on a shaft F and the corresponding wheel D^{4*} on the right of Fig. 2 is carried fast on a nested shaft F¹. The shafts F, F¹ each carry printing drums that are suitably situated in-

the machine. Any number of such shafts may be nested one within the other each carrying its own drum and operated by its own quadrant and intermediate mechanism.

Secured to the wheel B is a ratchet wheel 70 G and secured to the wheel B¹ is another ratchet wheel G¹. Carried free on a rocking shaft H are pawls G², G³ engaging with the wheels G, G¹ respectively. The shaft H carries pins H¹, H² that are adapted to engage 75 pins G⁴, G⁵ that are carried by arms on the pawls G², G³; the pawls are maintained in engagement by springs G⁶.

The rocking shaft H is controlled by the printing lever J (Fig. 2) which is pivoted 80 at J¹ to a plate K carried at one end of the machine. On a part secured to the printing lever is a cam J² (Fig. 1). To a bracket L secured to the end plate K¹ of the machine is pivoted a lever L¹ whereof one end bears 85 against the cam J² while the other end is connected by a link L² to an arm L³ fast on the rocking shaft H. The arm L¹ is kept in engagement with the cam J² by a spring L⁴. The cam J² with the arm L¹ and link L² are 90 omitted from Fig. 2 for the sake of clearness.

In addition to the pawl G³ another pawl M coöperates with the ratchet wheel G¹. This pawl is carried by a sleeve M¹ that is 95 free on a shaft M². Fast on the sleeve M¹ is an arm M³, and this carries a pin M⁴ that bears against the quadrant A. A spring M⁵ that has engagement with the sleeve M¹ maintains the arm M³ with its pin against 100 the quadrant. The shaft M² has on it a second sleeve M⁶ that carries an arm M⁷ having a pin M⁸ that bears against the quadrant A¹. The sleeve M⁶ is shown in the figure broken away, but in actual practice it would be 105 carried on to a point opposite the ratchet wheel of the mechanism for the next lower order of value (in this case the pence) where it would carry a pawl similar to the pawl M that would engage the ratchet wheel 110 of the pence mechanism. When the quadrants are in the position of rest, shown in Fig. 1, the arms M³, M⁷ are held back against the action of their controlling springs, so that their pawls lie free of the ratchet 115 wheels with which they coöperate. This arrangement insures that the pounds shall be first zeroized, and then as the quadrant A returns to its zero position, it engages the pin on the arm M³ and this arm lifts the 120 pawl M out of the shillings ratchet owing to the attachment with the arm M¹ and allows the shillings mechanism to return to zero, "carrying-on" being effected during the process if the number of shillings, when 125 added to that already represented by the total is greater than 19. In the same way it will be seen that the pence and farthings mechanism will operate in turn, "carrying-on" from a lower order to a higher always,

being prevented until the direct operation by the quadrants allotted to the mechanism for recording such higher order of value has been completed. To still further aid the 5 release in succession of the pounds, shillings, etc., and to render the withdrawal of the pawls G^2 G^3 as easy as possible, the pins H^1 H^2 are set at different angles so that the pawls G^2 G^3 are released in succession. The 10 pin H^1 may be arranged to come into operation first and then the pin H^2 and after that the pin for the pence pawl, and so on.

The operation of this part of the mechanism is as follows:—The operation of the 15 keys connected with the quadrants A , A^1 , displaces the latter in a clockwise direction, as indicated by the arrows, distances proportional to the amount represented by the 20 keys operated. This rotates the wheels B , B^1 in a counter-clockwise direction and also the ratchet wheels G , G^1 . The pawls G^2 , G^3 which allow rotation in this direction prevent a clockwise rotation under the action of the springs a , so that the quadrants 25 remain locked in the positions to which they have been moved. The movement of the wheels B , B^1 has also rotated the wheels D , D^1 , and as each of these carry pawls as already described, which can slide over their 30 co-operating pin wheels D^2 when moved in a clockwise direction, the pin wheels and consequently those parts of the total mechanism connected therewith are not operated by this movement. The printing key J is now 35 however depressed by the user, and such movement in addition to effecting the printing of the item recorded by the item drums, (as the result of their displacement by the quadrants A , A^1) releases the pawls G^2 , G^3 to allow the item drums and mechanism to 40 be zeroized. It will be seen that the cam J^2 has a concentric portion j which is followed by an eccentric portion j^1 . While printing is being effected, the concentric portion j 45 traverses the end of the lever L^1 but after printing has been effected the eccentric part j^1 comes opposite the lever L^1 and allows the engaging end of the lever to rise under the action of the spring L^4 . This movement 50 causes the rocking shaft H to be turned in the direction of the arrow (Fig. 1), so that the pins H^1 , H^2 are made to bear against the pins G^4 , G^5 on the pawls G^2 , G^3 ; the pawls are thus withdrawn from their engagement with the ratchet wheels G , G^1 55 whereupon the quadrants A , A^1 being spring controlled return to the position of rest, and thus bring the parts back to zero. During this zeroizing movement, however, the pawls 60 controlled by the wheels D , D^1 engage the pin wheels D^2 of the total mechanism, one of such pin wheels only being shown and carry these wheels back a distance varying according to the degree of advancement of 65 the pawls, and this is so arranged that the

total recorded by the drums shall always be advanced an amount corresponding to the item that has just been zeroized. This mechanism is fully described and illustrated in the patent hereinbefore referred to. 70

It should be noted that if both quadrants A , A^1 with their mechanism were allowed to return at the same time, and it so happened that during this return movement the shillings were "carrying-on" to the pounds while 75 the pounds mechanism were still in motion, the amount carried on would be lost, and for this purpose the pawl M , which constitutes the main feature of this invention, is introduced. Directly the pounds quadrant, that 80 is the quadrant representing the highest order of value in the machine under consideration is advanced for recording the item, the pawl M is allowed to drop into engagement with the ratchet wheel G^1 of the 85 shillings mechanism, and thus the shaft C^1 and wheel B^1 are locked against clockwise movement, that is movement in the zeroizing direction. Directly, however, the quadrant A returns to its zero position it engages the 90 pin on the arm M^1 , and through this connection with the shaft M^1 , the pawl M is lifted out of engagement with the ratchet wheel M^1 , and the shillings mechanism, or the next highest order of value in the 95 machine under consideration, is zeroized.

Similarly that pawl which would be controlled by the arm M^1 locks the wheel that controls the pence mechanism when the shillings quadrant A^1 is operated. 100

In Fig. 2, the item drums are indicated diagrammatically at N , and the total drums at N^1 . Opposed to the item drums is the platen O that is carried by a rocking arm O^1 . This arm is spring controlled, and is 105 operated by a cam P , and auxiliary stop P^1 , controlled by the printing lever, as described in my earlier specification No. 894982 of 4th August 1908. These parts need not be described in the present specification, but they 110 are all carried on the plate K already referred to that is free to slide on the end plate K^1 of the machine. The plate K is held in place by shouldered-screws K^2 that engage slots K^3 and permit the plate to slide in a 115 vertical path. Normally the plate is locked down in the position shown, by a spring controlled catch L^* , but pivoted to the end plate K^1 of the machine at L^{21} is an arm L^{31} having an operating handle L^{41} . The arm carries a pin L^5 that engages a horizontal slot L^6 in the plate K , and at the end of the slot and in the upper face of the same is a recess L^7 . 120

When it is desired to print the total the 125 catch L^* is drawn back by hand and the arm L^5 is swung up into a vertical position so that the pin L^5 rests in the recess L^7 . In this position the platen O is raised to the level of the total drums N^1 , as shown in 130

chain line, and by depressing the printing key J , the parts will operate in the same manner as for printing the items, except that the platen will now strike the drums N^1 instead of the drums N .

It will be noted that by the item mechanism being locked by the retaining pawls G^2 , G^3 after each operation, the keys that have been operated remain down, and the operator can, at a glance, see whether he has put down the proper keys before printing, if he so desires. It follows from this that until the mechanism of each higher order of value that has been operated by the keys has transferred its item, by the direct operation of the quadrant, to the total recording mechanism, the mechanisms of the lower orders will not zeroize, but as the quadrant A of the pounds mechanism comes to its position of rest it carries back the arm M^3 so that the pawl M of the shillings mechanism is released; the quadrant A^1 will in the same manner, by means of the arm M^7 , release the pence mechanism and so on, as will be readily understood.

What I claim as my invention and desire to secure by Letters Patent is:—

1. A register having a plurality of item recording devices of different orders, means for actuating said item recording devices, a total recording device, actuating mechanism connecting the total recording device and the item recording devices, and means for controlling said actuating mechanism, said controlling means being arranged to permit the total recording device to be successively actuated by the item recording devices in a predetermined order; substantially as described.
2. A register having a plurality of item recording devices of different orders, means for actuating said devices, locking devices for said item recording devices, means for zeroizing each of said item recording devices, a total recording device, actuating

mechanism for said total recording device arranged to be actuated by the zeroizing movements of the item recording devices, and means for successively releasing the locking devices for the item recording devices; substantially as described.

3. A register having a plurality of item recording devices of different orders, a sector for each of said item recording devices, means for zeroizing each of said sectors, a total recording device, actuating devices between each of said item recording devices and the total recording device arranged to be actuated during the zeroizing movement of the sectors, and a pawl arranged to retain the actuating connections between the total recording mechanism and one of the item recording mechanisms in a locked position during the zeroizing of one of the sectors; substantially as described.

4. A register having a plurality of item recording devices of different orders, a sector for each of said item recording devices, means for zeroizing each of said sectors, a total recording device, actuating devices between each of said item recording devices and the total recording device arranged to be actuated during the zeroizing movement of the sectors, and a pawl arranged to retain the actuating connections between the total recording mechanism and one of the item recording mechanisms in a locking position during the zeroizing of one of the sectors, together with means for releasing said pawl when the first sector is moved to its zeroizing position; substantially as described.

In testimony whereof I have signed my name to this specification in the presence of two subscribing witnesses.

ARTHUR JAMES POSTANS.
